UNITED STATES PATENT OFFICE

2,431,416

ADJUSTABLE SCREEN DOOR GUARD

Charles Richard Nagel, Burbank, Calif.

Application November 24, 1945, Serial No. 630,632

2 Claims. (Cl. 160—136)

1

This invention relates to improvements in adjustable screen door guards.

Heretofore, adjustable screen door guards have been provided consisting of a plurality of cross members pivotally connected together and providing a lattice adapted to be positioned in the frame of a screen door adjacent the screen therein. These screen door guards are adjustable as to width by reason of the pivotal connections between the members forming the lattice and consequently may be adjusted to fit the frame of any screen door. The ends of the members forming the lattice are frequently curled into scrolls having apertures therein through which screws or other fasteners may be driven into the stiles and bottom rail of the screen door frame to mount the guard in place.

An objection to the conventional screen door guard as above described resides in the fact that the upper ends of members of the lattice that are intermediate the upper corners of the lattice are unbraced. These members are frequently arranged at approximately the center of the screen and approximately waist high. Consequently these ends which are unbraced are most conveniently located to be pushed in pushing the door open. As these ends are unsecured to the door frame and are unbraced frequent pushing thereon tends to weaken the guard and to loosen it from the door frame.

An object of the present invention is to provide an improved adjustable screen door guard which is so constructed as to adequately brace the upper ends of the members forming the lattice which upper ends are located intermediate the upper corners of the lattice so that even though these ends are severely pushed they will not tend to weaken the guard or tend to loosen the guard from the door frame.

More specifically, an object of the invention is to provide an improved adjustable screen door guard consisting of pivotally connected diagonally arranged members forming a lattice and wherein the upper ends of those members which form the upper corners of the lattice are bent horizontally inward and to provide a push bar which slidably receives these ends so as to permit of the adjustment of the guard and which embraces the upper ends of those members that are located intermediate the corners so as to brace and steady them.

With the foregoing and other objects in view, which will be made manifest in the following detailed description and specifically pointed out in the appended claims, reference is had to the

2

accompanying drawings for an illustrative embodiment of the invention, wherein:

Figure 1 is a view in front elevation of the improved adjustable screen door guard.

5 Fig. 2 is a vertical section taken substantially upon the line 2—2 upon Fig. 1.

Fig. 3 is a vertical section taken substantially upon the line 3—3 upon Fig. 1.

Referring to the accompanying drawings 10 wherein similar reference characters designate similar parts throughout, the improved screen door guard comprises a plurality of diagonally arranged crossed members some of which such as those illustrated at 10 and 11 may be regarded 15 as main members in that they extend from corner to corner of the guard. Other members such as those indicated at 12 may be regarded as intermediate members in that their ends are arranged intermediate the corners of the guard. These 20 members are preferably formed of heavy metal strips arranged edgewise to the plane of the guard and have twisted portions indicated at 13 where they cross to facilitate their being riveted together such as by rivets 14. Any other 25 means for pivotally connecting the members of the lattice where they cross each other may be employed if so desired. The ends of the members are preferably curled to provide scrolls such as those indicated at 15 on the main members and 30 16 on the intermediate members. These curled or scrolled portions have perforations therein adapted to receive screws or similar fasteners indicated at 17 that are adapted to be driven into the stiles and bottom rail of the door frame. As 35 the members of the lattice are pivotally connected together the lattice may be adjusted as to width to accommodate itself to any size of screen door.

In accordance with the present invention the 40 upper ends of the main members 10 and 11 instead of being scrolled have their ends bent horizontally inward as indicated at 18 and 19 and a push bar generally indicated at 20 is provided. This push bar is in the form of an inverted channel the ends of which are closed by bending the 45 downwardly extending sides 21 inwardly towards each other as indicated at 22 to enclose the horizontal portions 18 and 19. This provides a sliding engagement between the push bar 20 and the 50 corners of the lattice that does not interfere with the adjustment of the guard. Although the angular relationship between the main members 10 and 11 and the horizontal portions 18 and 19 may vary slightly on adjustment of the guard 55 this is taken care of by the upper ends of the

main members 10 and 11 merely flexing slightly to maintain the portions 18 and 19 horizontal within the push bar. The sides 21 of the push bar intermediate its ends extend downwardly and embrace the sides of the scrolled portions 23 on the intermediate members 12 at the top of the lattice. As these scrolled portions are unsecured to the push bar or to the portions 18 and 19 they may merely slide with respect thereto on adjusting the guard to any particular door frame.

As the upper ends of the main members 10 and 11 are rigidly secured to the stiles of the door frame such as by the screws 17 and the push bar encloses the horizontal portions 18 and 19 the push bar is sturdily mounted between the stiles and serves to brace and support the scrolled portions 23. This consequently braces and strengthens the entire lattice at its top where it is unsecured to the door frame. Consequently even though the push bar or the portions 23 are severely pushed in opening the door it will not cause the guard or lattice to warp or rack and to become loosened within the door frame.

From the above-described construction it will be appreciated that the improved guard is materially stronger at the points where the conventional screen door guard is weak and at the same time the structure is such that it does not interfere with the adjustment of the guard to fit various sizes of door frames.

Various changes may be made in the details of

construction without departing from the spirit and scope of the invention as defined by the appended claims.

I claim:

- 5 1. A screen door guard comprising a lattice formed of pivotally connected members, the upper ends of members which provide the upper corners of the lattice being bent horizontally inward, and a push bar encircling the inwardly bent portions and slidably relatively thereto.
- 10 2. A screen door guard comprising a lattice formed of pivotally connected members, the upper ends of members which provide the upper corners of the lattice being bent horizontally inward, and a push bar encircling the inwardly bent portions and slidably relatively thereto, said push bar having downwardly extending sides embracing the upper ends of the lattice forming members that are disposed intermediate the upper corners thereof.
